TREATMENT OF HYDROCARBON OILS

Jean Delattre-Seguy, Chicago, Ill., assignor, by
mesne assignments, to Universal Oil Products
Company, Chicago, Ill., a corporation of Dela-
ware

Application February 11, 1931, Serial No. 514,941
Renewed May 8, 1934

6 Claims. (Cl. 196—49)

The invention relates to the treatment of hydrocarbon oils and refers more particularly to the conversion of hydrocarbon oils of a relatively high boiling range into products of a more valuable character.

More specifically, the invention contemplates the utilization of hydrogenating reactions in conjunction with a cracking process, the heavier products from cracking reactions being subsequently hydrogenated and some of the heavier products from the hydrogenating zone being returned to a point in the cracking reaction zone to arrest the progress of the cracking reaction by causing a suitable temperature drop, the hydrogenated fractions themselves in turn being sufficiently heated thereby to insure later substantial removal of gasoline fractions.

In a preferred and specific embodiment of the process of the invention relatively heavy hydrocarbon oils are pumped under pressure through a heating element wherein they receive heat to initiate desired reactions and the heated products then pass through two reaction zones in series. Prior to entering the second reaction zone the products are cooled, either by the admission of relatively cooler intermediate products and/or residue from an auxiliary hydrogenating unit or by the admission of raw oil charging stock, or both. The vapors from the second reaction zone pass through suitable fractionating devices from which vapors of desired boiling point range are removed, condensed and collected and unvaporized reflux condensates are returned for further treatment along with the raw oil. Suitable auxiliary means are utilized to control the boiling point range of the hydrocarbon vapor mixture leaving the last fractionator. The non-vaporized portions of the cracking reaction products separating as heavy liquids in the secondary reaction zone are then brought to suitable temperatures either by heating or cooling, and are passed to an arrangement of reaction chambers into which hydrogen or hydrogen-containing gases are admitted to effect hydrogenating reactions, suitable catalysts being present therein to reduce the time factor and to facilitate hydrogenation. The hydrogenating chambers may be employed in series or in parallel and the hydrogen employed therein may be suitably preheated if desired. Vapors from the hydrogenating chambers, preferably after substantial pressure reduction, pass to a fractionating device in which partial separation of the fractions boiling within a range suitable for gasoline is effected, these vapors being condensed and collected, a suitable portion of the

condensate being employed to control the boiling point of the hydrocarbons issuing from the top of the fractionator. The liquid reflux condensates from the fractionator, owing to the comparatively low temperature of the entering vapors, due both to the relatively low temperatures employed in the hydrogenation chambers and the subsequent pressure reduction, contain material amounts of hydrocarbons boiling within the motor fuel range. These reflux condensates are pumped back into the line between the two reaction chambers of the cracking unit, wherein they cool the cracking reaction products to temperatures sufficient to arrest undesirable side reactions and are in turn heated to a temperature which insures effective removal of their gasoline fractions in the fractionating devices of the cracking unit.

As an example of the operation of the process of the present invention the attached diagrammatic drawing which forms part of the present specification shows one form of an apparatus that may be employed. Oil to be treated which may be typified by a crude petroleum from which gasoline fractions have been removed by well-known distillation methods is pumped by pump 3 from line 1 controlled by valve 2. By a suitable manipulation of valves 5, 7, 7' and 9' in line 4, 6 and 8' the charge may be proportioned among three points of admission. Through line 4 controlled by valve 5 it may be admitted at some suitable level in a primary fractionator 23 receiving the vapors from the cracking unit. When allowed to flow through line 8' by opening valve 9' it meets the products of cracking at a stage prior to their admission to chamber 20 in which the final reactions of decomposition or recombination are controlled at some predetermined point. When allowed to flow through valve 7' and into line 8 it mixes therein with reflux condensate from fractionator 23 which is being returned to heating element 9 for further heating and conversion, pump 96 taking suction through line 93' with suitable setting of valves 94', 95' and 98. A portion of the reflux condensate may be removed through line 97 controlled by valve 98. Suitable pressures and temperatures are maintained during the passage of the combined feed from line 8 through heating element 9 to effect a certain portion of the desired conversion. In some instances further conversion is allowed to take place without further addition of heat in a chamber which is typified by reaction chamber 12 through which the products enter and leave through lines 10, valves 11 and lines 15 and valves 14 respectively. In other instances it may be

found best to omit the reaction chamber in which case the products produced by the heating element 9 traverse the by-pass line 13 containing valve 14, enter line 15 and pass through valve 16 and line 17 into chamber 20. In the passage of the reaction products through line 17 they are controllably cooled by either the relatively heavy products from the bottom of the fractionator in the hydrogenation unit or the raw oil feed as previously described. Provision is also shown in line 18 controlled by valve 19 whereby the relatively heavy products from the hydrogenating unit may be admitted at some level in the chamber 20 instead of being admitted into line 17. The vapors from chamber 20 pass through line 21 controlled by valve 22 into fractionator 23 and the vapors from fractionator 23 pass through line 24 controlled by valve 25 into fractionator 26 in series. The final product of gasoline boiling point range from the cracking unit passes through line 27 controlled by valve 28 to condenser 29 thence to line 30 controlled by valve 31 to receiver 32, fixed gases and vapors being released to storage through line 33 controlled by valve 34 and the liquid of desired boiling point range being similarly released through line 35 controlled by valve 36. For accurate control of the boiling point range of the vapors leaving fractionator 26 a certain portion of the liquid products from receiver 32 is pumped controllably by pump 99 from line 100 and valve 101 through line 102' and valve 102 to the top of fractionator 26. For partial control of the boiling point range of the vapors leaving fractionator 23, pump 108 is shown in position to pump the bottoms from fractionator 26 through line 103, valve 104 and line 105 controlled by valve 107 thence on the discharge side through line 110 controlled by valve 109 to the top of fractionator 23. The relatively heavy bottoms from chamber 20 pass through line 37 and either through line 41 controlled by valve 39 or to pump 41' through valve 38, the pump serving to increase pressure at subsequent points in the hydrogenation unit when found desirable. From line 41 the evaporator bottoms are preferably passed through valve 42 to heating element 45 suitably disposed in furnace B wherein they are controllably heated to a predetermined temperature found most suitable to their subsequent hydrogenation. By the use of valve 43 a portion or all of the evaporator bottoms may be diverted around heating element 45 and a convenient control of temperature is at times thus effected. From valves 43 or 44 the evaporator bottoms pass to hydrogenating chambers 47 and 47'. By suitable manipulation of valves 48, 20 and 68 in lines 46, 49, 66 and 68 the hydrogenating chambers 47 and 47' which typify any number of such chambers may be used either in series or in parallel, with regard to the vaporous products. By the use of line 51 containing valve 52 the liquid portions of the oils undergoing treatment in the hydrogenating chambers may be transferred. The hydrogenating chambers operate under conditions of temperature and pressure found most suitable to effect desired reactions and preferably contain catalytic material typified by metals or their oxides alone or in combination which may be deposited upon inert substances or may be maintained in suspension by means of vigorous mechanical agitation. The hydrogen necessary for the desired conversions is taken from line 55 through valve 56 by pump 57 and preferably pre-heated in heating element 59 disposed in furnace 75 C with valves 58 and 60 open or a certain amount

may be diverted around the heating element 59 by the use of line 62 containing valve 61, a convenient method of control being thus provided. The hydrogen then at suitable temperature passes through line 63 and valve 64 into line 64' which is manifolded so that hydrogen necessary for the desired reactions may be introduced to the hydrogenating chambers through lines typified by 63 and 63' containing valves 65 and 65' respectively. Means are shown in lines 53 and 53' controlled by valves 54 and 54' respectively for discharge of spent catalytic materials from the hydrogenating chambers. Vapors from the hydrogenating chamber pass through lines 66 controlled by valves 67 and 72 to fractionator 73 wherein hydrocarbons of boiling point range suitable for use as motor fuel are separated and passed through line 74 controlled by valve 75 to condenser 76, the condensed products along with uncondensable gases passing through line 77 controlled by valve 78 into receiver 79. Fixed gases may be removed to suitable storage through line 80 controlled by valve 81 and the mixture of liquid products suitable for use as gasoline similarly disposed of through line 82 controlled by valve 83. For accurate control of the boiling point range of the vapors issuing from fractionator 73 pump 113 may draw a certain portion of the liquid end products through line 111 and valve 112 and discharge them at the top of fractionator 73. The bottoms from fractionator 73 constituting reflux condensate from the hydrogenating unit pass through line 84 controlled by valve 85 to pump 86 which discharges into line 87. Likewise, hydrogenated vapors from the chambers 47 and 47' may pass in whole or in part through line 70 controlled by valve 71 into line 87. From this line the reflux condensate may be returned as previously indicated to a point in the cracking unit by pump 93 which discharges through line 94 controlled by valve 95 either alone or in admixture with unvaporized oil from hydrogenating chamber 47' which may be taken by pump 90 to line 88 and valve 89 from line 91 controlled by valve 92 into the line 87 and thence to pump 93 and line 94. It will be obvious from the foregoing description that the process of the present invention comprises some very desirable features. The ordinary yield of cracked products of boiling point range suitable for motor fuel has been augmented by the provision of a more or less distinct hydrogenating unit which can be employed as a balance wheel in effecting desired conversions over a wide range. The cracking unit and the hydrogenating unit are shown not only in chemical but in physical interrelation, particularly with regard to heat transfer, and means have been disclosed for producing several types of end products for use as motor fuel. Pressures employed in the cracking reaction shown may be of the order of from 100 to 400 lbs. per sq. in. more or less, they may be differential at succeeding points in the units or may be equalized with respect to each other and temperatures employed in the cracking reaction vary from 850 to 950° F. approximately, these conditions together with the rate of feed which controls the time factor being varied to suit the characteristics of the oil being treated. The pressures employed in the hydrogenating zone are in general higher than those employed in the cracking zone and may be as high as 3000 lbs. per sq. in. The temperature employed in the hydrogenating reaction are somewhat lower than those employed in the cracking

reactions and may be of the order of 750 to 875° F. more or less. Temperatures employed may, however, vary over a wide range from 600 to 1200° F. and pressures up to very high super-atmospheric may be used. The catalysts employed in the hydrogenating chambers may be variously finely divided metals or their oxides alone or in combination as, for example, iron, nickel, cobalt, molybdenum, chromium, vanadium, etc. or mixtures of the same as well as oxides and other compounds may be employed.

As an example of an operation falling within the scope of the present invention a 25 gravity topped crude is fed to the cracking unit, 50% of the feed being sent to the fractionator, 25% used for cooling between the reaction chambers and 25% fed direct to the heating element. Pressure maintained on the first of small reaction chambers of the series is 200 lbs. per sq. in. and the temperature at the exit of the heating element 940 to 945° F. After passing through the small reaction chamber the reflux of raw oil and products from the hydrogenating zone lowers the temperature to 850° F. There may be produced continuously in the cracking unit to which 1000 bbls. per day of raw oil is fed, 550 bbls. of gasoline of approximately 425° F. end point, 100 bbls. of intermediate oils suitable for reprocessing, 250 bbls. of residual oil charged to the hydrogenating unit and an equivalent loss of 10% in fixed gases. The 250 bbls. of residual oil which has a gravity of approximately 10° A. P. I. is treated in the hydrogenators at a pressure of approximately 2000 lbs. per sq. in. and temperatures of approximately 750° F. in the presence of suitable catalysts producing an equal number of barrels of a synthetic crude of 35 gravity containing 40% of hydrocarbons of gasoline boiling point range. The vapors pass directly to the fractionator.

Owing, however, to the lower temperatures employed and the additional loss in heat due to the release in pressure at the fractionator from a portion of the hydrogenating equipment only 30% of the gasoline boiling point hydrocarbons is evolved from the fractionator. The bottoms from this fractionator are then pumped into the stream of products issuing from the smaller reaction chamber of the cracking unit wherein they received sufficient heat to enable subsequent effective removal of hydrocarbons of gasoline boiling point. There may be thus produced an overall yield of 65% of hydrocarbons of gasoline boiling point range without the production of appreciable quantities of coke and with the production of a minimum amount of fixed gases.

What I claim is:

1. A process which comprises subjecting heavy hydrocarbon oil to cracking conditions of temperature and pressure, commingling a cooling oil with the thus cracked oil to prevent excessive decomposition thereof, separating the commingled oils into vapors and unvaporized oil, reacting the unvaporized oil with hydrogen under temperature and pressure conditions adequate to convert a substantial portion thereof into hydrogenated lighter hydrocarbons, removing vapors from the thus treated unvaporized oil and de-phlegmating the same to separate heavier from lighter fractions thereof and to form a gasoline-containing reflux condensate, and introducing such gasoline-containing reflux condensate to said cracked oil as said cooling oil.
2. A process which comprises subjecting heavy hydrocarbon oil to cracking conditions of temperature and pressure, commingling a cooling oil

with the thus cracked oil to prevent excessive decomposition thereof, separating the commingled oils into vapors and unvaporized oil, reacting the unvaporized oil with hydrogen under temperature and pressure conditions adequate to convert a substantial portion thereof into hydrogenated lighter hydrocarbons, removing vapors from the thus treated unvaporized oil and condensing the same to form a gasoline-containing condensate, and utilizing a portion of said gasoline-containing condensate as said cooling oil.

3. A process which comprises subjecting heavy hydrocarbon oil to cracking conditions of temperature and pressure, commingling a cooling oil with the thus cracked oil to prevent excessive decomposition thereof, separating the commingled oils into vapors and unvaporized oil, reacting the unvaporized oil with hydrogen under temperature and pressure conditions adequate to convert a substantial portion thereof into hydrogenated gasoline hydrocarbons, and introducing a portion of the gasoline products of the hydrogenation into said cracked oil to constitute said cooling oil.

4. A process which comprises heating hydrocarbon oil to cracking temperature under pressure while flowing in a restricted stream through a heating zone and subsequently discharging such heated oil into an enlarged zone, cracking the oil by heat and pressure during such treatment, separating the cracked products into vapors and residue, reacting the residue with hydrogen under temperature and pressure conditions adequate to convert a substantial portion thereof into hydrogenated lighter hydrocarbons, fractionating the resultant vapors to condense heavier fractions thereof, commingling resultant reflux condensate with the heated oil discharging from the heating zone into the enlarged zone, fractionating the vapors evolved in the enlarged zone independently of the first-named vapors thereby forming additional reflux condensate, supplying such additional reflux condensate to said heating zone, and finally condensing the fractionated vapors.

5. A conversion process which comprises cracking hydrocarbon oil by heat and pressure while flowing in a restricted stream through a heating zone, separating the cracked oil into vaporous and liquid conversion products in an enlarged zone, removing liquid products from the enlarged zone and supplying the same to a hydrogenating zone, reacting the liquid products in the hydrogenating zone with hydrogen under temperature and pressure conditions adequate to convert a substantial portion thereof into lighter hydrogenated hydrocarbons, separating the resultant hydrogenated products into vapors and unvaporized oil and fractionating the former to condense heavier fractions thereof, commingling resultant reflux condensate and at least a portion of said separated unvaporized oil with the hot cracked oil discharged from the heating zone, and finally condensing the fractionated vapors.

6. A conversion process which comprises cracking hydrocarbon oil by heat and pressure while flowing in a restricted stream through a heating zone, commingling with the hot cracked oil a hydrogenation residue formed as hereinafter set forth, separating the resultant mixture into vaporous and liquid conversion products in an enlarged zone, fractionating the vaporous products to condense heavier fractions thereof and supplying resultant reflux condensate to the heating zone, removing liquid products from the enlarged

zone and supplying the same to a hydrogenating zone, reacting the liquid products in the hydrogenating zone with hydrogen under temperature and pressure conditions adequate to convert a substantial portion thereof into lighter hydrogenated hydrocarbons, separating the resultant 5 hydrogenated products into vapors and unvaporized oil, commingling at least a portion of the separated unvaporized oil with the hot cracked

oil discharged from the heating zone to constitute said hydrogenation residue, fractionating said vapors independently of the vaporous products from the enlarged zone and combining reflux condensate formed by this fractionation with the unvaporized oil to be commingled with said hot cracked oil, and finally condensing the fractionated vapors. 5
